(57) **CLAIM**

The ornamental design for a roller sign thimble with sign, as shown and described.

DESCRIPTION

FIG. 1 is a perspective view of a roller sign thimble showing our new design without the sign inserted to provide clarity; FIG. 2 is a left side view of the thimble without the sign inserted to provide clarity thereof, the right side view is identical;

FIG. 3 is a top plan view of the thimble without the sign inserted to provide clarity thereof, the bottom view is identical;

FIG. 4 is a top plan view of FIG. 7, the bottom plan view is identical with a sign attached therein;

FIG. 5 is a front view of FIG. 7, the back view is identical with a sign attached therein;

FIG. 6 is a left side view of FIG. 4, the right side view is identical with a sign attached therein; and,

FIG. 7 is a perspective view of a roller sign thimble with a sign attached therein.
